UNITED STATES PATENT OFFICE.

WILLIAM H. EDDY, OF WORCESTER, MASSACHUSETTS, ASSIGNOR TO N. A. LOMBARD COMPANY, OF WORCESTER, MASSACHUSETTS, A CORPORATION OF MASSACHUSETTS.

PUPPET FOR CARDING-ENGINES.

SPECIFICATION forming part of Letters Patent No. 743,261, dated November 3, 1903.

Application filed May 9, 1902. Serial No. 106,617. (No model.)

To all whom it may concern:

Be it known that I, WILLIAM H. EDDY, a citizen of the United States, residing at Worcester, in the county of Worcester and Commonwealth of Massachusetts, have invented a new and useful Improvement in Puppets for Carding-Engines, of which the following is a specification, accompanied by drawings, forming a part of the same, in which—

10 Figure 1 represents a portion of the framework of the carding-engine with one of my improved puppets held therein. Fig. 2 is a perspective view of the puppet with my improved dust-guard applied thereto and shown in a closed position. Fig. 3 represents the same with the dust-guard opened, and Fig. 4 is a perspective view of a modified form.

Similar reference - letters refer to similar parts in the different views.

20 My invention relates to the bearing or stand for supporting the journals of those card-cylinders in a carding-engine known as "workers" or "strippers," and it has for its object to provide a dust-guard by which the journal-bearing is protected from dirt or dust; and it consists in the application to the **U**-shaped bearing of a pair of hinged covers, by which the open or **U**-shaped bearing is closed, as hereinafter described, and set forth in the annexed 25 claims.

Referring to the accompanying drawings, A denotes a portion of the frame of a carding-engine in which the puppets or bearings for the workers or strippers are supported, 30 Fig. 1 showing one such held in position.

B denotes a puppet provided with a shank B', which is held in the framework A in the usual manner and is provided at its upper end with a **U**-shaped journal-bearing C, adapted 35 to receive the journal D of a worker or stripper. The open end of the bearing is closed when the journal is placed in position by means of covers E E, provided at each end with arms F F, which are hinged to the sides 40 of the puppet by screws G G. The covers E are arranged to be swung apart on their pivotal screws G, as shown in Fig. 3, in order to allow the journal D to be inserted when the covers are brought together until their op-

posing edges E' are brought into contact. 50 The lower ends of the arms F are extended beyond the pivotal screws G, as shown at F' F', so that when the covers E E are thrown apart sufficiently to allow the journal D to be inserted within or removed from the bearing 55 the ends F' F' will be brought into contact, as shown in Fig. 3, and thereby limit the outward movement of the covers E E. When the covers E E are brought together with their edges E' E' in contact, the rear edges E² are 60 brought into contact with the sides of the puppet, as shown in Fig. 2, thereby making a closed joint and preventing the introduction of dirt into the open bearing, and when closed the curved edges F² are brought 65 into contact with the cylindrical surface of the journal D, as shown in Fig. 2.

In Fig. 4 the construction of the dust-guard or cover is substantially the same as that shown in Figs. 2 and 3 with the exception 70 that the opening in the bearing to receive the journal is placed at an angle with the shank B' instead of parallel thereto, as shown in the preceding figures.

The ends F' F' of the arms F are raised 75 above the bottom of the journal-bearing C when the covers E E are separated to allow the journal D to be introduced, so that the pressure of the journal on the ends F' F' will rock the arms F and bring the covers E E together, automatically closing the bearing C, as shown in Figs. 1 and 2, while the act of lifting the journal D out of the bearing will press the journal against the curved edges F² and automatically separate the covers E 80 E until they pass a vertical line passing through the pivotal screws G G, so that gravity will bring the ends F' F' together and hold the covers apart.

What I claim as my invention, and desire 90 to secure by Letters Patent, is—

1. In a puppet for carding-engines, the combination with a **U**-shaped bearing having one side open to receive a rotating journal and a cover by which the open side of said bearing 95 is closed, said cover being removable from the open side of the bearing to allow the journal to be inserted and removed.

2. In a puppet for carding-engines provided with a **U**-shaped bearing, the combination with said bearing, of a pair of hinged covers adapted to swing over and close the open end 5 of the bearing, substantially as described.

3. The combination with the **U**-shaped bearing of a puppet for carding-engines, of a pair of covers adapted to close the open end of said bearing, said covers having arms 10 at their opposite ends pivotally connected to the sides of the puppet, substantially as described.

4. The combination with the **U**-shaped bearing of a puppet for carding-engines, of 15 a pair of covers **E**, **E'** provided with abutting edges **E'**, **E'**, arms **F** at the ends of said covers with said arms pivotally connected to the puppet and having projecting ends **F'** arranged to come in contact and limit the

swinging movement of said covers, substantially as described. 20

5. The combination with the **U**-shaped bearing of a puppet for carding-engines, of a pair of covers pivotally connected to the puppet and adapted to close the open end of 25 said bearing, said covers having ends **F'**, **F'**, adapted to be raised above the bottom of the journal-bearing when the covers are separated, so that the pressure of the journal on said ends will bring the covers together and 30 automatically close the bearing, substantially as described.

Dated this 6th day of May, 1902.

WILLIAM H. EDDY.
